US00D689541S

(12) **United States Design Patent**
Kim

(10) **Patent No.:** **US D689,541 S**
(45) **Date of Patent:** **** Sep. 10, 2013**

(54) **TYPEFACE**

(71) Applicant: **Kia Motors Corporation**, Seoul (KR)

(72) Inventor: **Hyun Tae Kim**, Gyeonggi-do (KR)

(73) Assignee: **Kia Motors Corporation**, Seoul (KR)

(**) Term: **14 Years**

(21) Appl. No.: **29/433,739**

(22) Filed: **Oct. 4, 2012**

(30) **Foreign Application Priority Data**

Jun. 29, 2012 (KR) 30-2012-0031755

Jun. 29, 2012 (KR) 30-2012-0031757

Jun. 29, 2012 (KR) 30-2012-0031758

(51) **LOC (9) Cl.** **18-03**

(52) **U.S. Cl.**

USPC **D18/24**

(58) **Field of Classification Search**

USPC D18/24-33; 101/398, 699; 400/484
